TRACK CIRCUIT APPARATUS FOR GOVERNING BOTH WAYSIDES AND CAB SIGNALS

Robert M. Gilson, Pittsburgh, Pa., assignor to The Union Switch & Signal Company, Swissvale, Pa., a corporation of Pennsylvania

Application December 22, 1945, Serial No. 636,703

2 Claims. (Cl. 246—34)

1

My invention relates to track circuit apparatus, and more particularly to track circuit apparatus for governing both wayside and cab signals.

In railway signaling the track circuit of a track section is supplied in many cases with direct current for energizing a track relay when the section is unoccupied and with alternating current for operation of a cab signal when a train moves through the section. There are well defined operating characteristics prescribed for track circuits and these characteristics are best met in one manner when direct current is used and in a somewhat different manner when alternating current is used. Also, when a track circuit is to be supplied with direct current for one function and with alternating current for another function, it is in the interest of economy and simplicity that a single source of power is used.

Accordingly, a feature of my invention is the provision of novel and improved track circuit apparatus for control of both wayside and cab signals.

Another feature of my invention is the provision of improved track circuit apparatus to supply current for energizing a direct current track relay and for operating a cab signal from a single source of alternating current.

Other features, objects, and advantages of my invention will appear as the specification progresses.

To attain the foregoing features, objects and advantages of my invention, I provide a novel circuit network for connecting a source of alternating current to the track circuit to supply current through a full wave rectifier for energizing the track relay when the section is unoccupied, and through a half wave rectifier for operation of the cab signal when a train moves through the section and for also reenergizing the track relay when the train vacates the section.

I shall describe five forms of apparatus embodying my invention and shall then point out the novel features thereof in claims.

In the accompanying drawings, Figs. 1, 2, 3, 4, and 5 are diagrammatic views showing five different forms of track circuit apparatus, each of which forms of apparatus embodies my invention.

In each of the several views like reference characters are used to designate similar parts.

Referring to Fig. 1, the reference characters $1a$ and $1b$ designate the track rails of a railway over which traffic normally moves in the direction indicated by an arrow, and which rails are formed with a track section $D-E$, the section $D-E$ being ordinarily one section of a series of sections of a signaling system. The rails $1a$ and $1b$ are arranged to be included in a track circuit which also includes a track relay, connected across the rails at one end of the section and a source of

power connected across the rails at the other end of the section.

As here shown, the track relay is a direct current track relay DTR having a winding 10 connected across the rails adjacent the entrance end D of section $D-E$. The power source comprises two track transformers $ET1$ and $ET2$ having primary windings 11 and 12 , respectively, connected to a source of alternating current, the terminals 10 of which source are indicated BX and CX . This source of alternating current may be a commercial power line supplying 60 cycle alternating current, but preferably the source would supply alternating current of the frequency of the order of 100 cycles per second, such 100 cycle current being used in many railway signaling systems. It is to be understood that my invention is not limited to alternating current of any particular frequency, and current of any suitable frequency can be used.

The primary windings of transformers $ET1$ and $ET2$ are connected to the power source through contacts of an approach controlled relay VR , primary winding 11 of transformer $ET1$ being connected to terminals BX and CX through an obvious circuit including front contact 13 of approach controlled relay VR , primary winding 12 of transformer $ET2$ being short circuited through front contact 14 of relay VR and connected to terminals BX and CX through back contact 15 of relay VR . Thus transformer $ET1$ or $ET2$ is supplied with power according as the relay VR is picked up or is released.

The secondary windings of transformers $ET1$ and $ET2$ are connected to the rails at exit end E of the section through a rectifier here shown as a four arm bridge rectifier 19 . Secondary winding 13 of transformer $ET1$ is connected to input terminals 17 and 18 of rectifier 19 and output terminals 20 and 21 of the rectifier are connected to the rails by output terminal 20 being connected to rail $1b$ through lead wire 22 and output terminal 21 being connected to rail $1a$ through wire 23 , secondary winding 24 of transformer $ET2$, wire 25 , resistor 26 and lead wire 27 .

It follows that normally, that is, when relay VR is energized and the track section $D-E$ is unoccupied, the track relay DTR is energized by full wave rectified current supplied to the circuit from transformer $ET1$ through the full wave rectifier 19 . As shown in Fig. 1, winding 24 presents low impedance to the flow of current because its primary winding 12 is short circuited by front contact 14 of relay VR . This permits the normal full wave rectified pulsation in the voltage applied across the rails, which is an aid in shunting the track by the wheels and axles of a car, due to the relatively high peaks of the pulsating voltage for a given average value of voltage.

The relay VR is controlled through an obvious

line circuit including front contact 28 of track relay DTR and thus the relay VR is energized when the section D—E is unoccupied and is de-energized in response to the train entering the section to shunt the relay DTR. With relay VR released to open front contacts 13 and 14 and close back contact 15, power is removed from track transformer ET1 and is applied to the track transformer ET2 and half wave rectified current is supplied to the track rails from secondary winding 24 of transformer ET2 through the rectifier 19 serving as a half wave rectifier. When the top terminal, as viewed in Fig. 1, of secondary winding 24 is positive, current flows through wire 23, terminal 21 to terminal 20 of rectifier 19 through the rectifier elements in the forward direction, lead wire 22, rail 1b, train shunt to rail 1a, lead wire 27, resistor 26, and wire 25 to the other terminal of the secondary winding 24. During the half cycle of the power source that the lower terminal of secondary winding 24 is positive, the flow of current to the track circuit is blocked by the rectifier elements of rectifier 19. Thus, half wave rectified current is supplied to the track circuit and such current is available for inductive operation of cab signals when the section is occupied. When the train moving through section D—E vacates the section, the half wave rectified current is also available for initial energization of the track relay DTR, and that relay is picked up to restore the apparatus to its normal condition.

It is apparent that by proper proportioning of the parts, the apparatus of Fig. 1 will supply full wave rectified current suitable for proper energization of the track relay DTR when the section is unoccupied and will supply half wave rectified current suitable for inductive operation of cab signals when a train moves through the section, and such half wave rectified current is available for initial energization of track relay DTR when the train vacates the section.

The apparatus disclosed in Fig. 2 is the same as that of Fig. 1, except for the track transformer. In Fig. 2 a track transformer ET3 is provided with a primary winding 29 and two secondary windings 30 and 31. Primary winding 29 is connected to terminals BX and CX of the power source, secondary winding 30 is connected to input terminals 17 and 18 of rectifier 19 through a front contact 32 of relay VR, and the output terminals of rectifier 19 are connected across the rails at exit end E of the track section, the output terminal 20 being connected to rail 1b through lead wire 22 and output terminal 21 being connected to rail 1a through wire 23, front contact 33 of relay VR, wires 34 and 25, resistor 26, and lead wire 27.

At such time as relay VR is released to open front contacts 32 and 33, secondary winding 30 is disconnected from the track circuit and secondary winding 31 of the track transformer is connected thereto, the connection including rectifier 19 as a half wave rectifier. During the half cycle the top terminal of secondary winding 31 is positive, current flows through back contact 35 of relay VR, wire 23, terminal 21 to terminal 20 of rectifier 19 through the rectifier elements in their forward direction, lead wire 22, rail 1b, train shunt, rail 1a, lead wire 27, resistor 26 and wire 25 to the lower terminal of secondary winding 31. During the other half cycle of the power source, the flow of current to the track circuit is blocked by the rectifier elements of rectifier 19.

The relay VR is controlled through a line circuit including front contacts 28 of the track relay

DTR, the same as in Fig. 1, and consequently full wave rectified current is supplied from secondary winding 30 of the track transformer to energize the track relay DTR when the section is unoccupied and half wave rectified current is supplied to the track circuit from secondary winding 31 for operation of cab signals when a train occupies the section. The half wave rectified current is also available to initially energize the track relay DTR and restore the apparatus to normal condition when the train vacates the section.

The apparatus disclosed in Fig. 3 is different from that of the apparatus of Fig. 1 in the arrangement of the rectifier, and to include a shunt path around the rectifier. Primary windings 11 and 12 of the two track transformers are connected to the power source through contacts of the relay VR the same as in Fig. 1. Secondary winding 16 of track transformer ET1 is connected to the outside terminals of rectifiers 8 and 9 in series. The junction terminal of rectifiers 8 and 9 is connected to rail 1b through lead wire 22 and a mid terminal of secondary winding 16 is connected to rail 1a through resistor 26, secondary winding 24 of transformer ET2 and lead wire 27.

Rectifiers 8 and 9 are poled reversed to each other and thus when the track section D—E is unoccupied and relay VR is picked up, the track circuit is supplied with full wave rectified current from secondary winding 16 through the rectifiers 8 and 9, and when relay VR is de-energized in response to a train entering the section to shunt track relay DTR, the opening of front contacts 13 and 14 discontinues the supply of full wave rectified current and half wave rectified current is supplied to the track circuit from the secondary winding 24 of track transformer ET2 through resistor 26, lower half of secondary winding 16, and rectifier 9. However, in Fig. 3, a shunt path including a resistor 36 is connected around the rectifier 9 and resistor 26 through back contact 37 of relay VR, and such shunt path serves to increase the alternating component of the track circuit current so that when the section D—E of Fig. 3 is occupied, the half wave rectified current has a large alternating current component for operating the cab signals. Resistor 36 would usually have considerably greater resistance than resistor 26 so that the direct current component of the track circuit current supplied when the relay VR is released will be of sufficient magnitude to energize the track relay DTR and restore the apparatus to its normal condition when the train vacates the section.

In each of Figs. 1, 2 and 3 it is obvious that a coder can be provided for the apparatus and a coder contact interposed in the connection of lead wire 22 or 27 and the track circuit provided with coded current for operation of a code following track relay and coded cab signals.

The apparatus disclosed in Fig. 4 is different from the apparatus of Fig. 2 in that a coder is provided, the track relay DTR is replaced by a direct current code following relay DTR1, and a reactor and a capacitor are included in the circuit network through which the track transformer is connected to the track rails.

In Fig. 4, a portion of secondary winding 30 is connected across input terminals 17 and 18 of rectifier 19, the portion of the winding to be used being preselected according to the particular track section to be supplied. The output terminals 20 and 21 of rectifier 19 are connected across 75 the rails by terminal 20 being connected to rail

1b through a reactor 38 and lead wire 22; and terminal 21 being connected to rail 1a through winding 31, resistor 26, contact 40 of coder CP and lead wire 27. A capacitor 41 is connected around rectifier 19 and reactor 38.

Secondary winding 30, in combination with the rectifier 19 and the capacitor 41, which preferably is of relatively large capacitance, maintain a unidirectional voltage across the capacitor 41 of the polarity indicated in Fig. 4. Secondary winding 31 provides an alternating current component to the track circuit, the path for which includes lead wire 22 from rail 1b, capacitor 41, secondary winding 31, resistor 26, coder contact 40, and lead wire 27 to rail 1a. Capacitor 41 is thus a mutual element in the direct current and alternating current supply circuits and acts very much like a battery to provide a direct voltage in series with the alternating voltage with consequent direct current and alternating current components in the current in the rails. The direct current component is effective to energize the direct current track relay DTR1 when the section is unoccupied, and the alternating current component serves to operate a cab signal when a train occupies the track section. The reactor 38 prevents the alternating current component from unbalancing the currents between the two legs of each pair of legs in rectifier 19 and thus prevents any appreciable direct current component in secondary winding 30, and also reduces the ripple in the rectified voltage supplied by secondary winding 30 and rectifier 19 to capacitor 41.

In Fig. 5, secondary winding 30 of transformer ET3 is connected across the outside terminals of rectifiers 8 and 9 in series and poled reverse to each other. The junction terminal of rectifiers 8 and 9 is connected to rail 1a through resistor 26, coder contact 40 and lead wire 27, and a mid terminal of winding 30 is connected to rail 1b through reactor 38 and lead wire 22. Thus a full wave rectified current is supplied to the track circuit from secondary winding 30 and such current is available to energize track relay DTR1 when the section is unoccupied.

Secondary winding 31 is connected across the track rails through capacitor 41, back contact 42 of approach controlled relay VR and resistor 26. Thus when relay VR is released an alternating current is supplied to the rails from secondary winding 31 and such current is available to operate a cab signal when a train occupies the section. The capacitor 41 serves to block the direct current from winding 31, and the reactor 38 serves to prevent the alternating current from unbalancing the rectifiers. Thus in Fig. 5, the direct current component and the alternating current component of the current in the rails can be independently adjusted.

Track circuit apparatus such as here disclosed has the advantages that from a single source of alternating current a track circuit is provided at times with a rectified direct current having a relatively small alternating current component for energization of a direct current track relay, and at other times with a current having a relatively large alternating current component for operation of cab signals, this latter current also having a direct current component effective to initially energize the track relay.

Although I have herein shown and described but five forms of track circuit apparatus em-

bodying my invention, it is understood that various changes and modifications may be made therein within the scope of the appended claims without departing from the spirit and scope of my invention.

Having thus described my invention, what I claim is:

1. In track circuit apparatus for a track section, the combination comprising, a direct current track relay connected to the rails at the entrance end of said section, a first and a second track transformer, an approach relay controlled to a first and a second position through a contact of said track relay, means including a first position contact of said approach relay to connect a primary winding of said first transformer to a source of alternating current, means including a second position contact of said approach relay to connect a primary winding of said second transformer to said source of alternating current, a current rectifier means adaptable of being used either as a full wave rectifier or as a half wave rectifier, a first circuit means to connect a secondary winding of said first transformer to the rails at the exit end of the section through said rectifier means as a full wave rectifier to energize said track relay with full wave rectified current, and a second circuit means to connect a secondary winding of said second transformer to the rails at the exit end of said section through said rectifier means as a half wave rectifier to supply a half wave rectified current for operation of cab signals.

2. In track circuit apparatus for a track section, the combination comprising, a direct current track relay connected to the rails at the entrance end of said section, a first and a second track transformer, an approach relay controlled to a first and a second position through a contact of said track relay, means including a first position contact of said approach relay to connect a primary winding of said first transformer to a source of alternating current, means including a second position contact of said approach relay to connect a primary winding of said second transformer to said source of alternating current, a full wave rectifier, a secondary winding of said first transformer connected across the input terminals of said rectifier, and means including a secondary winding of said second transformer to connect the output terminals of said transformer across the rails at the exit end of the section, whereby full wave rectified current is supplied to energize said track relay when the section is unoccupied and half wave rectified current is supplied for operating cab signals when a train occupies the section.
